UNITED STATES PATENT OFFICE

115,348

DESIGN FOR A COMBINED AUTOMOBILE HOOD AND FENDER

Paul A. Meyer, Detroit, Mich., assignor to General Motors Corporation, Detroit, Mich., a corporation of Delaware

Application December 19, 1938, Serial No. 81,871

Term of patent 7 years

To all whom it may concern:

Be it known that I, Paul A. Meyer, a citizen of the United States and resident of Detroit, county of Wayne, State of Michigan, have invented a new, original, and ornamental Design for a Combined Automobile Hood and Fender, of which the following is a specification, reference being made to the accompanying drawing, forming a part thereof.

Fig. 1 is a front perspective view of a combined automobile hood and fender showing my new design.

Fig. 2 is a front elevational view, on an enlarged scale, of the combined automobile hood and fender design shown in Fig. 1.

Fig. 3 is a fragmentary sectional view, taken on the line 3—3 of Fig. 2.

The characteristic features of the design are shown in solid lines.

I claim:

The ornamental design for a combined automobile hood and fender, substantially as shown and described.

PAUL A. MEYER.
